UNITED STATES PATENT OFFICE

MONTAGU BLATCHFORD, OF HALIFAX, ENGLAND, ASSIGNOR TO JOSEPH
WILD & CO., OF NEW YORK, N. Y.

DESIGN FOR A CARPET-PATTERN.

Specification forming part of Design No. 5,883, dated June 4, 1872.

Specification describing a new and original Design for Carpet, invented by MONTAGU BLATCHFORD, of Halifax, in the county of York, England.

The accompanying photograph fully illustrates my invention.

This invention relates to a new design for carpets and other fabrics; and consists in the new configuration of the main figures, of which one is oblong and contains four heart-shaped ornaments around a lozenge-shaped center, while the other main figure is octagonal with two overlying quatrefoils in the middle. Both figures contain wreaths of flowers, as shown.

I claim as my invention—

The design for a carpet, as shown.

MONTAGU BLATCHFORD.
